UNITED STATES PATENT OFFICE

JOHN A. YERKES, OF LONG BEACH, CALIFORNIA

PUMPING APPARATUS

Application filed March 6, 1928. Serial No. 92,702.

This invention relates to pumping apparatus, and particularly to the type of pumping apparatus designed for use where space is limited, such as in oil wells. More specifically 5 the invention embodies that type of pumping apparatus in which the cylinder and piston and valve of a single cylinder pump-engine and a pump are arranged and constructed to operate in tandem.

10 The general object of the invention is to provide a practical pumping apparatus of the character stated in which simplicity and convenience of structural arrangement, and ease and efficiency of operation, will be combined.

A more particular object is to provide a pumping apparatus as above set forth which may be operated by fluid under pressure and without the use of a sucker rod.

20 With the above and other objects in view, the invention consists in the novel and useful provision, formation, construction and interrelation of parts, members and features, all as shown in the drawings, hereinafter described, and finally pointed out in claims.

In the drawings:

Figure 1 is an elevation of the pumping apparatus, partly in section, shown in pumping position in an oil well, with the oil well 20 casing shown in section;

Figures 2, 3 and 4 are fragmentary views partly in elevation and partly in section, on a larger scale than Fig. 1, of the upper, intermediate and lower portions respectively of 35 the pumping apparatus;

Figures 5, 6 and 7 are fragmentary longitudinal sectional views on a larger scale than Figs. 2 to 4 inclusive, of the engine valve, the engine and its pump coupling and the pump 40 respectively of the apparatus;

Figure 8 is a vertical longitudinal section on a considerably larger scale than Fig. 5 of the engine valve;

Figure 9 is a horizontal section taken on 45 line 9—9 of Fig. 6;

Figure 10 is a fragmentary longitudinal section of the valve cylinder;

Figure 11 is a fragmentary view partly in elevation and partly in vertical section of the 50 valve cylinder;

Figure 12 is a horizontal section of the engine valve taken on line 12—12 of Fig. 5;

Figure 13 is a horizontal section of the engine valve taken on the line 13—13 of Fig. 5;

Figure 14 is a horizontal section of the engine valve taken on the line 14—14 of Fig. 5;

Figure 15 is a horizontal section of the valve, taken on the line 15—15 of Fig. 5;

Figure 16 is a vertical sectional view of the engine valve and connecting parts embodying a modification of the invention;

Figure 17 is a horizontal section taken on line 17—17 of Fig. 16;

Figure 18 is a cross sectional view on the line 18—18 of Fig. 16;

Figure 19 is a horizontal section taken on line 19—19 of Fig. 16;

Figure 20 is a vertical sectional view of the casing head embodying the invention.

Corresponding parts in all the figures are 70 designated by the same reference characters.

Referring with particularity to the drawings, the apparatus includes generally an oil pump P, an engine E, an engine valve V, an operating fluid pump O, and a fluid tank T. 75

The pump P may be of standard construction including a pump cylinder p, a plunger p', pump rod p², inlet I, a shoe 1, standing valve 2, and plunger valve 3.

The engine E includes a cylinder e, a piston e', a piston rod e² connected to the lower end of said piston and a valve rod e³ connected to the upper end of said piston. Ports e⁴ and e⁵ are provided in the lower and upper ends respectively of cylinder e. The piston rod e² is coupled at its lower end to the upper end of the pump rod p² by a coupling e⁶.

The upper end of the cylinder p is screw-connected at 5 to the lower end of a pump tube 6, the upper end of which tube is screw-connected at 7 to the lower end of a hollow coupling K. The coupling K is formed with a conical lower end portion 8 which is provided with an annular groove 9 in which is fitted a gasket 10. The coupling K is located in the lower end of a pump return tube R, the lower end of the coupling extending downwardly through a hollow plug or shoe r which is screw-seated at 11 in the lower end of said tube and is formed with a conical seat 12 on 100

which seats the lower conical end 8 with its gasket 9 whereby the oil in the well is sealed off from said tube and the engine, valve and other parts in said tube. The coupling K is provided with a pair of outlets 13 arranged diametrically opposite each other, which outlets communicate with the lower end of the pump return tube R. On the upper end of the coupling K is formed the lower head 14 of the engine cylinder e, which head is screw seated at 15 in the lower end of said cylinder, and is formed with a packing box 16 through which the lower piston rod e² extends. The packing box 16 includes a gland 17 fitted in the lower end of the box, gland bolts 18 and gland springs 19. On the lower end of the packing box 16 is formed an annular groove 20 and an annular external flange 21 below said groove, in the periphery of which flange 20 are provided notches 22 in which are fitted the upper ends of bolts 18, the heads 23 of said bolts fitting in the groove 20. The bolts 18 are soldered in the notches 22 with lead 24, while the heads 23 of said bolts are soldered to the upper wall of groove 20 with lead 25. The gland 17 has an external flange 26 on its lower end which is provided with openings 27 through which extend the bolts 18. The bolts 18 have threads 28 on which 30 screw nuts 29 and lock nuts 30 below the nuts 29. Collars 31 are fitted on the bolts 18 upon the nuts 29 and the springs 19 surround the bolts 18 between the said collars and the gland flange 26 and force the gland 17 upwardly in the packing box 16 against the packing 32 therein to maintain the packing in fluid-tight contact with the piston rod e².

The valve V includes a valve cylinder v, a hollow valve plunger v', reciprocatively 40 mounted in said cylinder, a hollow auxiliary plunger v², an inlet v³ and an outlet v⁴.

The lower end of the valve cylinder v is welded at its periphery at 35 to the upper end of the engine cylinder e and the upper valve 45 rod e³ extends through the valve cylinder and the valve plunger v'. A metal packing 36 is fitted in the lower end of the valve cylinder v and in the upper end of the engine cylinder e, through which packing reciprocates the 50 upper rod e³, whereby fluid is prevented from passing from the lower end of the valve cylinder into the upper end of the engine cylinder, or vice versa.

The cylinder v is provided with a bore 40 55 extending downwardly therein of a uniform diameter, from its upper end to a shoulder 41 in the lower portion thereof, from which shoulder downwardly the bore is reduced slightly in diameter. In the lower end of the 60 cylinder bore 40 is fitted a bushing 42 which rests at its lower end upon the shoulder 41 and is formed in its upper end with a bearing 43 in which the lower end of the plunger v' is slidably mounted. In the bore 40 above the 65 bushing 42 is fitted a bushing 44, of larger

internal diameter than the bushing 42, the bushing 44 resting at its lower end upon the upper end of the bushing 42 and surrounding the auxiliary plunger v² which is slidably mounted between the bushing 44 and the plunger v'. In the bore 40 above the bushing 44 is fitted a bushing 45 which rests at its lower end upon the upper end of the bushing 44. The bushing 45 has an internal diameter somewhat larger than the external diameter of the plunger v', but said bushing is formed with a bearing 46 in its lower end in which the plunger v' is slidably mounted. The cylinder v is provided with an internal thread 47 in the upper end of its bore 40, in which thread is seated an externally threaded locking sleeve 48, the lower end of which sleeve engages the upper end of the bushing 45 and locks said bushing together with the bushings 44 and 42 in the bore 40. A lock 50 nut 49 screws on the external thread of the locking sleeve 48 against the upper end of the valve cylinder v for locking the sleeve in locking position against turning. The upper end portion of the plunger v' is provided with a plurality of inlets 50. Below the inlets 50 the plunger v' is formed with an annular groove 51 in which is fitted a split friction ring 52 formed with an internal annular groove 53 in which is fitted a coil spring 54 which urges the sections of the ring outwardly into frictional contact with the inner surface of the bushing 45 for holding the plunger in any position into which it is moved. The plunger v' is provided with outlets 55 below the groove 51, which outlets rest within the lower part of bushing 45 immediately above the bushing bearing 46 when the plunger is in its uppermost position (see Figs. 5 and 8). The plunger v' is provided with a wide shallow annular external groove 56 below the outlets 55 which groove rests adjacent the inner surface of the auxiliary plunger v². In the lower end of the plunger v' is provided a plurality of outlets 57 which rest in the lower end of the bushing 44 immediately above the bearing 43 when the plunger is raised to its uppermost position (see Figs. 5 and 8). Heads 58 and 59 are fitted in the lower and upper ends of the plunger v' respectively, which heads have central bores 60 and 61 through which and the plunger extends the piston rods e³ of the engine E. A collar 62 is secured on the lower portion of the valve rod e³ for engaging the lower head 58 for effecting the upward stroke of the plunger, and a collar 63 is secured on the upper end of the piston rod e³ for engaging the upper head 59 for effecting the downward stroke of the plunger.

The cylinder v includes an inner cylindrical wall 65 and an outer cylindrical wall 66 spaced from the inner wall a short distance by outstanding longitudinal ribs 67 and two segmental ribs 68 on the inner wall, there being 130

preferably four of the ribs 67 spaced equidistantly apart and the ribs 68 being located near the upper end of the outer wall 66 and extending from a common longitudinal rib 67 respectively in opposite directions to the next ribs 67. Passages 70 and 71 are formed between certain of the ribs 67 and between the inner cylinder wall 65 and outer cylinder wall 66, while passages 72 and 73 are formed 5 between the other ribs 67 and between the cylinder walls below the rib 68, and passages 74 and 75 are formed between the ribs 67 and between the cylinder walls above the rib 68. The inner cylinder wall 65 is formed in the 10 upper portion thereof with three internal annular grooves 76, 77 and 78, spaced a short distance apart one below the other. The inner cylinder wall 65 is also formed with ports 80, 81, 82, 83, 84 and 85, which establish communication between the interior of 15 said cylinder wall and the passages 70, 71, 72, 73, 74 and 75 respectively. The passages 74 and 75 lead upwardly into the outlet v^4 .

The bushing 44 is provided with a plurality of ports 86, 87 and 88 which register with the annular internal grooves 76, 77 and 78 respectively in the inner wall 65 of the cylinder. The inner surface of the bushing 44 is provided with grooves 89 inclined outwardly 20 in a downward direction to the ports 86, and with grooves 90 inclined outwardly in an upwardly direction to ports 88, for the purpose hereinafter described.

The lower end of the auxiliary plunger v^2 25 is beveled upwardly in an inward direction as at 91 and the upper end of said plunger is beveled downwardly in an inward direction as indicated at 92 for the purpose hereinafter described. The auxiliary plunger v^2 is 30 formed with a wide annular groove 93 in its outer surface, the lower and upper edges of which groove are beveled. The plunger v^2 is provided with ports 94 extending from the bore of the plunger into the groove 93.

The valve cylinder outer wall 66 extends 45 downwardly over the engine cylinder e and is welded thereto at its lower ends as at 95 and 96, whereby the passages 70 and 71 are continued downwardly into communication with the engine cylinder port e^4 , while the 50 passages 72 and 73 are continued downwardly into communication with engine cylinder port e^5 .

On the upper part of the cylinder v is provided 55 an external thread 97 which is engaged by a thread 98 in the lower end of a tube 99 which forms the inlet v^3 , the upper end of which is provided with an internal thread 100.

The upper end of the inlet tube 99 is screw-seated 60 by means of its thread 100 on the lower externally-threaded end 101 of a gas cushion tube 102, the upper end 103 of which is reduced and the upper end of a fluid inlet tube 104 is welded in said reduced end 103, which

fluid inlet tube extends downwardly in the tube 102 nearly to the lower end thereof, there being a gas cushion chamber 105 formed in the tube 102 about the fluid tube 104. The upper end of the fluid inlet tube 104 and the gas cushion tube 102 are coupled by a screw coupling 106 to the lower end of a fluid intake tube 107, the upper end of which tube is connected at its upper end in a casing head 108 at the top of the oil well W. (See Figs. 1 70 and 20). The pump return tube R extends upwardly over the coupling K, engine E, valve V, gas cushion tube 102, and fluid intake tube 107, and is screw-connected at its upper end 107^a to the casing head 108, in communication with a casing head chamber 110. The pump P, coupling K, and pump return tube R with the parts enclosed therein extend down into the well W within the well casing C which is connected at its upper end 80 to the casing head 108 in the usual manner. The pump P, coupling K, and pump return tube R with the parts enclosed therein extend down into the well W within the well casing C which is connected at its upper end 85 to the casing head 108 in the usual manner.

The operating pump O includes a pump cylinder o, which intakes fluid, such as oil, from the tank T through an intake pipe 111 leading from said tank, and exhausts through 90 an exhaust pipe 112 which connects to the upper end of the casing head 108 in communication with the upper end of the fluid intake pipe 107. A swinging nozzle 113 is pivotally connected in the upper part of tank T to the pump intake tube 111 so that the inlet end of the nozzle will float in the upper strata of the oil 115 in said tank, so as not to take in any dirt or precipitate in the bottom of the tank. A pump return pipe 116 is connected to the 100 casing head 108 and leads from the chamber 110 of said head into the bottom of the tank T, said pipe being controlled by a valve 117. A delivery pipe 118, controlled by a valve 119, is connected to the casing head 108 and leads from the chamber 110, through which pipe the pumping apparatus delivers its product, such as oil, pumped from an oil well.

The operation of the invention is as follows: Assuming the valve plunger v' to be at the upper end of its stroke, as shown in Figs. 5 and 8, fluid such as oil under pressure is pumped by the operating pump O through exhaust pipe 112, fluid intake pipe 107, inlet 115 pipe 104, inlet v^3 , into the bore of locking sleeve 48, ports 50, valve plunger v' , plunger outlets 57, bushing ports 88, openings 82 and 83, passages 72 and 73, and port e^5 , into the upper end of the engine cylinder e , where the fluid forces the engine piston e' , its rods e^2 and e^3 , pump rod p^2 and pump plunger p' down, thus effecting the downward stroke of the engine E and oil pump P, the upper position of the auxiliary plunger v^2 preventing 120 the escape of any fluid from the passages 72 and 73 through ports 87, openings 84 and 85, passages 74 and 75 and outlet v^4 , but allowing fluid to escape from the lower end of the cylinder through passages 70 and 71, open- 130

ings 80 and 81, groove 76, ports 86, groove 93, ports 87, groove 77, openings 84 and 85, passages 74 and 75 and outlet v^4 . As the piston rod approaches the end of its downward stroke the collar 63 engages the upper plunger head 59 and forces the plunger v' downward. On the downward stroke of the plunger the ports 57 pass into the bearing 43 and are closed, which shuts off the fluid to the passages 72 and 73, while the ports 55 pass through the bearing 46 and admit fluid under pressure between the lower end of the bearing and the beveled upper end 92 of the auxiliary plunger v^2 , whereupon said plunger is forced down. As the plungers v' and v^2 continue their downward movement, the plunger v' moving slightly faster than the plunger v^2 , the lower edge of the annular groove 56 passes below the lower end of the auxiliary plunger v^2 and allows a sufficient amount of fluid in the space about the lower end of the auxiliary plunger to be displaced through said groove 56, ports 94, groove 93, and ports 87, groove 77, openings 84 and 85, passages 74 and 75 and outlet v^4 , by the downward movement of the auxiliary plunger, until the lower end of said plunger passes below the ports 88 in the bushing 44, whereupon the remaining oil below the auxiliary plunger within the bushing 44, is forced upwardly by said plunger during the remainder of its downward stroke, through the grooves 90 of the bushing 44 and out through the groove 93, ports 87, openings 84 and 85, passages 74 and 75 and outlet v^4 . With the engine piston e' and rod e^3 and the plunger v' and auxiliary plunger v^2 at the end of their downward stroke, fluid under pressure passes from the plunger v' through ports 55, upper end of the bushing 44, ports 86, groove 76, ports 80 and 81 and passages 70 and 71 into the lower end of the engine cylinder, whereupon the upward stroke of the engine piston e' and pump p' is effected. As the engine piston moves upward oil is forced out of the engine cylinder through port e^5 , passages 72 and 73, ports 82 and 83, ports 88, groove 93 in the auxiliary plunger, ports 87, groove 77, openings 84 and 85, passages 74 and 75 and outlet v^4 . As the engine piston e' and the valve rod e^3 approach the end of their upward stroke the collar 62 engages the lower plunger head 58 and effects the upward movement of the plunger v' . During the upward movement of said plunger the ports 55 pass through the bearing 46 and shut off the fluids from the plunger through bushing 44, ports 86, grooves 76, openings 80 and 81 and passages 70 and 71 to the lower end of the engine cylinder e' , while the ports 57 pass above the bearing 43, whereupon fluid under pressure passes from the plunger through said ports 57 between the upper end of bearing 43 and the lower beveled end 91 of the auxiliary plunger v^2 and effects the upward stroke of the aux-

iliary plunger, during the end of which stroke the oil in the upper end of the bushing 44 is forced by the upper end of the auxiliary plunger through the grooves 89 in the upper end of said bushing, out through ports 86, groove 76 and openings 80 and 81 into the passages 70 and 71, thus permitting the auxiliary plunger to reach the upper end of its stroke.

The pump plunger rod p^2 is of approximately one-half the cross-sectional area of the pump plunger p' , so that said plunger rod will displace one-half the oil which is lifted by the pump plunger p' on its downward stroke, and force said displaced oil up through the return tube R on said down stroke of the plunger, leaving only the remaining half of the oil displaced by the plunger on its downward stroke to be lifted by the plunger through the return tube R on the upward stroke of the plunger, thus effecting a uniform and continuous flow of the oil from the pump.

By introducing the pump through the lower end of the return tube R and enclosing the engine, valve and intake tube within said return tube, and by detachably sealing the lower end of the return tube it is possible to introduce the pump engine and intake into the well and pull the same therefrom independently of the return tube. It will be noted that the valve, engine and pump are disposed in tandem formation and constitute a string insertable in the return tube. Thus, the string may be "pulled" or withdrawn as a unit with all the operating parts and replaced.

The operation of the oil pump P pumps the oil out of the well through the tube 6, coupling K and its outlets 13, return tube R , casing head chamber 110 and delivery pipe 118.

The fluid pumped by the operating engine O from tank T through the valve V and into the engine E passes from the valve outlet v^4 into return tube R , mingling with the oil from the well and passing to casing head chamber 110. Part of the oil from chamber 110 passes through pipe 116 into the tank T .

When the valve plunger ports 55 and 57 are closed the fluid from the tube 104 backs up in the gas pressure chamber 102 and compresses the gas above the fluid in the chamber, thus cushioning the fluid and ensuring an even flow and pressure thereof.

In the modified form of the invention shown in Figs. 16 to 19 inclusive, the inlet tube 99 is eliminated and an auxiliary pump return tube R' is provided for returning the fluid pumped through the valve V into the engine back to the tank T . The lock sleeve 48 is formed with an enlarged extension 48^a on its upper end provided with an internal thread 48^b into which the lower threaded end 101 of the gas cushion tube 102 is screwed. 130

The lower end of the auxiliary return tube R' is provided with an internal thread r' which engages the thread 97 on the valve cylinder v. The passages 74 and 75 are extended upwardly in the valve cylinder so that the outlet e* discharges into the lower end of the auxiliary return tube R', whereby the fluid passing from the engine and valve are conducted back to the tank T independently of the oil pumped out of the well through the return tube R, the auxiliary return tube R' being within the return tube R.

It is obvious that various modifications, changes, and variations may be made in practicing the invention, in departure from the specific features so disclosed, without departing from the true spirit of the invention.

Having thus disclosed my invention, I claim and desire to secure by Letters Patent:

1. A pumping apparatus, including a pump, an engine, and engine valve, a hollow coupling for coupling said pump and said engine, through which coupling the engine piston rod and the pump rod extend, means for supplying fluid under pressure through said valve to the engine cylinder and piston to operate the engine and pump, a pump return tube surrounding the engine and coupling, a hollow plug in the lower end of said return tube formed with a seat, the lower end of said coupling being formed with a surface for engaging said seat, said coupling having outlets leading into said return tube.

2. A pumping apparatus, including a pump, an engine, and engine valve, a hollow coupling for coupling said pump and said engine, through which coupling the engine piston rod and the pump rod extend, means for supplying fluid under pressure through said valve to the engine cylinder and piston to operate the engine and pump, a pump return tube surrounding the engine and coupling, a hollow plug in the lower end of said return tube formed with a seat, the lower end of said coupling being formed with a surface for engaging said seat, said coupling having outlets leading into said return tube; a packing box in the upper end of said coupling through which the engine piston extends, and pressure means for compressing the packing in said packing box for maintaining fluid-tight contact of said packing and the piston rod.

3. A pumping apparatus, including a pump, an engine, and engine valve, a hollow coupling for coupling said pump and said engine, through which coupling the engine piston rod and the pump rod extend, means for supplying fluid under pressure through said valve to the engine cylinder and piston to operate the engine and pump, a pump return tube surrounding the engine and coupling, a hollow plug in the lower end

of said return tube formed with a seat, the lower end of said coupling being formed with a surface for engaging said seat, said coupling having outlets leading into said return tube; the upper end of said coupling being screw-seated in the lower end of the engine cylinder and forming the lower head of the cylinder, and a packing box in the upper end of said coupling surrounding the engine piston.

4. A pumping apparatus for wells comprising a casing head having a discharge for pumped liquid, a return tube depending from said casing, a shoe in said tube, a tubular string having a seat supported on said shoe and forming a fluid tight seal, said string being disposed within said tube to provide a space therebetween for flow of liquid to said casing head, a reciprocating pump including a plunger rod disposed in said string below said shoe, discharge outlets in said string above said shoe placing said pump in communication with said space, a reciprocating engine within said string and disposed above said discharge outlets, means sealing said engine from said outlets, passages in said tubular string for supply of operating fluid to said engine, said rod being operatively connected to said engine, a valve in said string operated by said engine and controlling the operating fluid for said engine, said tubular string forming a conduit for supply of operating fluid.

5. A pumping apparatus for oil wells comprising a return tube for pumped oil, a shoe in said return tube, a tubular string having a seat supported in said shoe to form therewith an insertable string: said string including in tandem formation, a reciprocating pump disposed below said shoe and having delivery ports opening to a space formed between said string and return tube; a reciprocating engine above said delivery ports and sealed therefrom, said engine being operatively connected to said pump; a control valve for said engine and operated thereby, the upper portion of said string constituting a conduit for supply of operating fluid to said engine.

6. A pumping apparatus for wells comprising a return tube for pumped liquid, a shoe in said return tube, a tubular string having a seat supported on said shoe to form therewith an insertable string: said string including in tandem formation a reciprocating pump having an inlet below said shoe and an outlet above said shoe communicating with said return tube; an engine operatively secured thereto; and a valve for said engine, said string constituting a conduit for supply of operating fluid to said engine.

In testimony whereof, I have signed my name to this specification.
